BOAT HOOK

Lawrence J. Calemmo, New York, N. Y.

Application November 30, 1949, Serial No. 130,088

8 Claims. (Cl. 114—230)

1

My invention relates to and comprises boat hooks which are of such construction as to permit their use either as a boat hook in the conventional manner, or as a mooring device, if so desired, whereby a line may be led through a ring, mooring eye, or the like, and brought back on board merely by use of the boat hook itself.

The difficulties inherent in the problem of mooring boats having relatively high free board especially in crowded harbors and under adverse weather or current conditions are well known. It is a great advantage to be able to handle this entire operation from the bow and expeditiously, both from the aspect of safety and smart seamanship.

The object of my invention is to provide an article of the character described capable of threading a line through a mooring eye and permitting the line to be drawn back on board or enabling its user merely to "hang on" to the eye, if so desired.

Another object is to provide an article of this type in which the means for actuating the parts to accomplish threading the line, as above described, are operable from the convenient handle portion of the boat hook when same is in use.

Another object is to provide an article of the character described in which a handle is furnished with a head having a hook portion formed integral therewith and carrying a detachable element connected to a leader with means for actuating the detachable element and controlling the leader.

A further object is to provide an article of this type which is of simple, durable construction whereby the above and other objects may effectively be attained.

Broadly, my invention comprises a boat hook having a handle portion and a head mounted thereon, said head and handle carrying cooperating means operably controlled from elements located on the handle and adapted to lead a line through an eye.

Referring to the accompanying drawings:

Fig. 1 represents a detail side elevation of my improved boat hook;

Fig. 2 represents a front elevation of same with the mooring ring omitted;

Fig. 3 represents a view similar to Fig. 1 with the swingable element in cooperative relationship with the detachable element mounted on the hook extremity;

Fig. 4 represents a detail side elevation with the parts in the position they assume when the hook has been disengaged from the mooring ring

2

after the leader has been threaded therethrough; and

Fig. 5 represents a detail vertical section, on an enlarged scale, taken in the plane of the line V—V of Fig. 2, looking in the direction of the arrows.

The boat hook comprises a handle 1 fitted at one end with a head 2 which is secured in place by the usual pin 3. The head 2 consists of a knob 4 and the customary hook 5 formed integral with the head. Handle 1 is suitably channeled or grooved at 29 throughout a substantial portion of one surface to accommodate an armored wire 6, one end of which is connected to an operating pull button 7 and the other end of which is operatively fastened to a latch 8 biased by spring 9 associated therewith.

Latch 8 is located to engage the outer extremity of a swingable lever 10 swung on the head 2 by means of a pin 11 to releasably hold said lever in its inoperative position, as shown in Figs. 1 and 2. Lever 10 is provided with a hole 12 and a cut-out portion 13 for purposes to be described below. Suitable mechanism such as a spring 14 mounted on pin 11 and engaged with the underside of lever 10 to urge same into operative position is provided.

A detachable element 15 is removably mounted in a recess 16 in the outer end of hook 5 and is held in proper relationship therewith by means of its tail portion 20 shaped to frictionally engage the walls of recess 16 and a centering pin 17. The latter cooperates with a longitudinal exterior groove 18 which extends along the hook 5 from the recess in its outer end to and through the knob 4 of head 2 (see Fig. 5). A spring actuated latch 19 is carried by element 15 and is swingably pinned therein by the pin 20 and urged outwardly by the coil spring 21.

Fastened to the rear end of element 15 is a flexible leader 22 of stainless wire or other suitable material, which leader ordinarily is led from element 15 through the groove 18 and down the back of handle 1 where the portion adjacent its end is surrounded by a spring 23 connected thereto. Said last named spring 23 is releasably held in a clip 24 mounted on handle 1 and enables the leader 22 to assist in holding element 15 in position on hook 5. The depending end of leader 22 is furnished with a snap hook 25 to operatively connect the leader to the mooring line 26 which may be furnished with an end fitting 27 of a design to accommodate hook 25.

The operation of my invention is as follows:

When it is desired to thread the mooring line

26 through a mooring eye 28, the parts are in the position shown in Fig. 1 with snap hook 25 connected to fitting 27 on the end of line 26. The boat hook is then seized by handle 1 and the hook 5 carrying detachable element 15 is passed through mooring eye 28. The operator then pulls button 7 connected to wire 6 and thereby moves latch 8 downwardly against the compression of spring 9 until said latch clears the end of swingable lever 10. As soon as lever 10 is clear of latch 8, spring 14 acts to rock lever 10 about its pivot pin 11 to the position shown in Fig. 3, the hole 12 in lever 10 passing over the detachable element 15 and its latch 19. Serving to limit the throw of lever 10 is the cut-out portion 13 which abuts the face of head 2, while latch 19 prevents disconnection of lever 10 from element 15. Spring 23 is then disengaged from clip 24 permitting leader 22 to be slackened off through groove 18 or cleared therefrom, if desired.

The head 2 on handle 1 is now pushed toward eye 28 until said eye contacts lever 10, thereby disengaging element 15 from hook 5. Hook 5 is then withdrawn from eye 28 and it will be seen that element 15 latched to lever 10 and connected to leader 22 is drawing same through said eye 28, as is shown in Fig. 4. This operation is continued until the operator can reach leader 22 and complete the threading of line 26 through eye 28 by pulling in the leader attached thereto.

When the mooring operation has been accomplished hook 25 may be detached from fitting 27; lever 10 unlatched from element 15; element 15 placed in recess 16; leader 22 led back through groove 18; spring 23 placed in clip 24; and all the parts returned to the positions shown in Fig. 1.

It will also be seen that if it is not desired to complete the mooring operation by threading the line through the ring, my invention enables the boat hook to be used in its customary fashion to "hang on" and "cast off" or "fend off" as seems advisable; the parts meanwhile being maintained in their positions as shown in Fig. 1 by the latch 8, leader 22 and clip 24.

It is evident that various changes may be resorted to in the construction, form and arrangement of the several parts without departing from the spirit and scope of my invention, and therefore I do not intend to be limited to the embodiment herein shown and described except as set forth in the following claims.

What I claim is:

1. A boat hook comprising, a handle, a head mounted thereon, a longitudinal channel extending throughout a substantial portion of the handle, an armored wire located in the channel, means for actuating the wire at its lower end, a spring latch attached to the upper end of said wire, a swingable spring biased perforated lever mounted on the head and restricted by said latch, a hook portion formed integral with said head, a recess in said hook, a detachable element mounted in said hook recess for coaction with said swingable lever, a latch carried by said detachable element, a groove in the head and hook interconnected with the hook recess, a leader attached to the detachable element at its inner end and located in said groove, a spring on the lower end of the leader, a clip mounted on the handle near its lower end to receive the said spring, and a snap hook on the lower end of the lead wire adapted to receive a cable.

2. A boat hook comprising a handle, a head mounted thereon, a hook formed integral with

said head, a detachable element mounted on said hook, swingable means mounted on the head, means for bringing said swingable means toward and into operative engagement with said detachable element, a latch on the handle normally restraining said swingable means, a remote release for said latch mounted in the handle, and means for securing said swingable means to said detachable element, the parts being so constructed and arranged that the operation of the latch release enables the swingable means to be biased into operative engagement with the detachable element.

3. A boat hook comprising a handle, a head mounted thereon, a hook formed integral with said head, a detachable element mounted on said hook, swingable means mounted on the head, means for bringing said swingable means toward and into operative engagement with said detachable element comprising a spring based on the head and biasing the swingable means toward said detachable element, a latch on the handle normally restraining said swingable means; a remote release for said latch mounted in the handle, and means for securing said swingable means to said detachable element, the parts being so constructed and arranged that the operation of the latch release enables the swingable means to be biased into operative engagement with the detachable element.

4. A boat hook comprising a handle, a head mounted thereon, a hook formed integral with said head, a recess in said hook, a detachable element mounted in said recess, swingable means mounted on the head, means for bringing said swingable means toward and into operative engagement with said detachable element, means for securing said swingable means to said detachable element and carried thereby, and means for holding the detachable element in said hook recess including a tail portion of said element provided with a centering pin riding in said hook recess, flexible means attached to said detachable element, and mechanical means on the handle so constructed and arranged that the flexible means is yieldingly held to the handle.

5. A boat hook comprising a handle, a head mounted thereon, a hook formed integral with said head, a recess in said hook, a detachable element mounted in said recess, swingable means mounted on the head, means for bringing said swingable means toward and into operative engagement with said detachable element, means for securing said swingable means to said detachable element and carried thereby, and means for holding the detachable element in said hook recess including a tail portion of said element provided with a centering pin riding in said hook recess, flexible means attached to said detachable element and mechanical means on the handle so constructed and arranged that the flexible means is yieldingly held to the handle, said last named means comprising a clip on the handle and a spring on the flexible means engageable by said clip.

6. A boat hook comprising a handle, a head mounted thereon, a hook formed integral with said head, a detachable element mounted on said hook, swingable means mounted on the head, means for bringing said swingable means toward and into operative engagement with said detachable element, the hole in said swingable means being aligned with said detachable element, means for limiting the outward swing of said swingable means comprising a cutout in the

base of said means engageable with the outer surface of the head, a latch on the handle normally restraining said swingable means, a remote release for said latch mounted in the handle, and means for securing said swingable means to said detachable element, the parts being so constructed and arranged that the operation of the latch release enables the swingable means to be biased into operative engagement with the detachable element.

7. A boat hook comprising a handle, a head mounted thereon, a hook formed integral with said head, a detachable element mounted on said hook, swingable means mounted on the head, means for bringing said swingable means toward and into operative engagement with said detachable element, a latch on the handle normally restraining said swingable means, a remote release for said latch mounted in the handle, and means for securing said swingable means to said detachable element, the parts being so constructed and arranged that the operation of the latch release enables the swingable means to be biased into operative engagement with the detachable element, said securing means comprising a spring biased latch mounted in the detachable element.

8. A boat hook comprising a handle, a head mounted thereon, said head comprising a knob, and a hook formed integral with said head and

projecting therefrom, a detachable element mounted on said hook at its outer end, swingable means mounted on the head, means for bringing said swingable means toward and into operative engagement with said detachable element, and means for holding the detachable element to the hook, said last named means comprising a longitudinal groove extending across the head, knob and hook portions and a flexible leader affixed

5 to the detachable element and located in said groove below the upper edges thereof, the parts being so constructed and arranged that the knob is available for fending off without damage to said flexible leader.
